UNITED STATES PATENT OFFICE

173,077

NARROW ELASTIC FABRIC

John V. Moore, Pawtucket, R. I., assignor, by mesne assignments, to Moore Fabrics, Pawtucket, R. I., a partnership

Application August 16, 1952, Serial No. 21,064

Term of patent 14 years

(Cl. D3—32)

To all whom it may concern:

Be it known that John V. Moore, a citizen of the United States, residing at Pawtucket, in the county of Providence and State of Rhode Island, has invented a new, original and ornamental Design for Narrow Elastic Fabric of which the following is a specification, reference being had to the accompanying drawing forming part thereof.

Fig. 1 is a plan view of a portion of narrow elastic fabric in strongly stretched condition;

Fig. 2 is a similar view of the same fabric partially relaxed;

Fig. 3 is a plan view of the same fabric in normal or unstretched condition; and

Fig. 4 is a substantially enlarged view of a small area of Fig. 3.

The design is particularly characterized by the novel and ornamental appearance of the center strip, as best shown in Fig. 4.

I claim:

The ornamental design for a narrow elastic fabric, as shown and described.
